Weyerhaeuser Company, Tacoma, Wash.

Original design application Oct. 20, 1969, Ser. No. 19,631,
now Patent No. 220,533, dated Apr. 20, 1971. Divided
and this application Aug. 31, 1970, Ser. No. 24,770

Term of patent 14 years

Int. Cl. D26—03

U.S. Cl. D48—31

FIG. 1 is a front elevational view of the light standard or similar article showing my new design.

FIG. 2 is a top plan view of the article of FIG. 1.

FIG. 3 is an enlarged cross-sectional view taken along line 3—3 of FIG. 1.

FIGS. 4 and 5 are enlarged cross-sectional views of additional embodiments of my design, the cross-section being taken on the embodiment on a plane identical to line 3—3 in FIG. 1, it being understood that those embodiments differ from FIG. 1 only in cross-section.

The lamps are shown in broken lines in FIGS. 1—2 for illustrative purposes only. The rear of the light standard is identical to the front.

This is a division of design application D. 19,631, filed Oct. 20, 1969, and now Design Pat. D. 220,533.

I claim:

The ornamental design for a light standard or similar article, as shown and described.
